UNITED STATES PATENT OFFICE.

RASMUS PEDERSON, OF MARQUETTE, NEBRASKA.

CULTIVATOR.

SPECIFICATION forming part of Letters Patent No. 790,387, dated May 23, 1905.

Application filed June 9, 1903. Serial No. 160,773.

To all whom it may concern:

Be it known that I, RASMUS PEDERSON, a citizen of the United States, residing at Marquette, in the county of Hamilton and State of Nebraska, have invented new and useful Improvements in Cultivators, of which the following is a specification.

My invention has relation to cultivators; and its primary object is to provide a new and useful device of this character having its shovels so arranged upon the machine-frame that their position with relation to the longitudinal center of the machine may be changed at the will of the operator, whereby it is possible to cause the shovels to follow a chosen direction regardless of the varied pull of the draft-animals.

Further objects of the invention are, first, to provide novel means for mounting the shovels upon the machine-frame to permit of their position being changed; second, to provide means for clearing the shovels of the ground or causing them to seek a penetration of any desired degree, and, third, to provide novel means for securing the shovels in applied position.

The invention consists of the construction, combination, and arrangement of parts herein-after fully described, claimed, and illustrated in the accompanying drawings, in which—

Figure 1 is a perspective view of a cultivator constructed in accordance with my invention. Fig. 2 is a central longitudinal sectional view thereof. Fig. 3 discloses views of means for securing the shovels in applied position. Fig. 4 is a detail perspective view of means for attaching disks to the cultivator.

Referring to the drawings by reference-numerals, 1 designates the side bars of a cultivator-frame, the same being connected at their rear ends by means of parallel bars 2, so relatively arranged that a space 3 is provided therebetween. To the front ends of these side bars 1 may be attached any suitable draft device, by means of which the cultivator may be drawn. Secured to the frame in advance of the transverse center thereof are bearings 4, which are adapted to journal upon the frame an axle 5, the depending arms 6 of which have their lower portions longitu-

dinally disposed to provide spindles 7. These spindles have journaled thereon carrying-wheels, which are adapted to support the front end of the machine, while the rear end thereof is supported by means of a caster-wheel 8. 55 The side bars 1 have their under faces provided with bearings 9, adapted to receive the reduced portions 10 of horizontally-disposed arms 11, that the latter may be journaled upon the machine-frame. The reduced portions of 60 the arms 11 are circular in cross-section to permit them to be turned in their bearings during the operation of lowering or raising the shovels. These arms have their adjacent ends connected by means of a link 12 and are adapted to support a plurality of pivotally-mounted drag-bars. The drag-bars each comprise two members arranged in different planes, one an upper member and the other a lower member. The upper members have their rear ends 70 bent downwardly and the upper members have their forward ends bent upwardly to provide horizontally and vertically disposed portions 15 and 16, respectively. The vertically-disposed portions 16 are adapted to pass through 75 apertures 17 in the horizontally-disposed portions 15 and are provided with a plurality of perforations, through which pins 17^a pass to hold the members in relative position and to permit of the vertical adjustment of the lower 80 member, which is adapted to have secured to its rear end the shovels, consequently providing for the shovels a vertical adjustment to regulate the depth of their penetration. Secured to the horizontal portions of the lower 85 members are a plurality of vertically-arranged shafts 17^b, the upper ends of which are adapted to freely pass through the horizontal portions of the upper members into and through bearings 18 in the arms 11 to pivotally mount 90 the drag-bars upon the frame. Each shaft has its upper end provided with a series of perforations, through one of which a pin 19 is adapted to pass to retain the shaft in applied position. This manner of connecting 95 the members and mounting the drag-bars upon the frame permits of the lower members having vertical adjustments and the drag-bars having pivotal connection with the frame.

The shovel-carrying frames, preferably two 100

in number, comprise arched members 19^a, each provided with a horizontally-disposed arm 20, which projects rearwardly from the lower ends of the arched members and at 5 acute angles with relation to their longitudinal centers. These arms are adapted to carry shovels of any improved construction, and from their arrangement upon the arched members dispose the shovels in either side of a fur- 10 row. The arms 20 are provided with plates 21, to which the rear ends of the drag-bars are secured. These shovel-carrying frames are adapted to be secured together by means of bars 21^a in order to prevent their lateral 15 relative displacement. The forward ends of each pair of drag-bars are received between parallel-arranged arms 22 to connect each pair that they may have imparted thereto relative movements, and said arms are con- 20 nected by means of a link 23. An operating-lever 24 is fulcrumed upon the link 12 to place its rear end in convenient reach of the operator and its front end over the link 23, to which it is secured. It is apparent in view 25 of the connection of each pair of drag-bars and their pivotal connection with the machine-frame that a movement of the lever in one direction or the other will cause the drag-bars to swing upon their pivots at an angle 30 with relation to the longitudinal center of the machine-frame, and consequently change the position of the shovels with relation to the longitudinal center of the machine-frame. To further explain this, it might be supposed 35 that the draft-animals were causing the machine to be drawn in a direction that would cause the shovels to leave the furrow if they were rigidly connected to the machine-frame; but by swinging the drag-bars either to the 40 right or left the position of the shovels is changed sufficiently to compensate for the irregular direction of the machine-frame.

The shovels may be secured to the arms 20 in the manner disclosed in Fig. 3 of the drawings—that is, by providing the arms with slots having the entrances thereto closed by removable caps 25 and the inner walls thereof corrugated to receive the corrugated heads 26 of the shovels. This manner of securing the 50 shovels in applied position prevents them from having a rotary movement and also permits the shovels being adjusted to any angle desired. In order that the shovels may be raised from or forced into engagement with the soil, 55 I provide means which may be manipulated by the operator of the machine. This means consists of parallel bars 27, spaced apart at their ends and between which the forward portions of the drag-bars freely pass, and a U- 60 shaped lever 28, having its free ends secured to the bar 27 and its rear end bent downwardly and passed through the space 3 to place the connecting-bar 29 thereof in convenient reach of the operator's feet. This lever has 65 connection, by means of rivets 29^a or their

equivalent, with the arms 11, which when the rear end of the lever is caused to move upward will be turned in their bearings, and consequently cause the shovels to be raised from engagement with the soil. A reverse move- 70 ment of the lever will cause the shovels to be brought into engagement with the soil, and their depth of penetration may be regulated by the amount of pressure the operator may bring to bear upon the connecting-bar 29. 75 The provision of the bars 27 beyond the pivotal point of the arms 11 facilitates the raising and lowering of the shovels in a manner that is obvious.

In Fig. 4 of the drawings I have disclosed 80 means for securing disks to the arched members 19^a, which means I will now describe. Secured to the depending arms of the arched member 19^a are segmental plates 30, which are spaced apart, as shown in the drawings, and 85 provided along their curved edges with depending flanges 31, having their lower ends horizontally disposed to provide channels 32. Secured to the plates at points adjacent the member 19 are depending arms 33, having 90 their lower ends provided with enlarged heads. Mounted upon these arms to have a vertical movement are sleeves 34. These sleeves are each secured to one end of shafts 35, the opposite ends of which are similarly provided 95 with sleeves to be mounted upon arms 36, which are adjustably carried by the plates. Disks 37 are adapted to be secured to the shafts, and they are adapted to be yieldingly 100 held in engagement with the soil by means of springs 38. The adjustment of arms 36 permits of disks being brought into engagement with the soil at any angle desired. The plates are provided along their front edges with extensions 39, by means of which they may be 105 secured to the drag-bars.

It is apparent from the above description, taken in connection with the accompanying drawings, that I provide a cultivator in which the position of its shovels may be easily, 110 quickly, and conveniently regulated to overcome or compensate for the irregularities in the pulling of the machine, that I provide a new and novel means for raising and lowering the shovels and causing them to seek any 115 desired degree of penetration, and that the construction, combination, and arrangement of parts are such as to enable me to produce a cheap, durable, and efficient device of the character described. 120

Having described my invention, what I claim is—

1. In a wheel-cultivator, the combination with a machine-frame, of arms journaled thereon, drag-bars carried by said arms, 125 shovels carried by said drag-bars, and means for turning the arms to raise or lower the shovels.

2. In a wheel-cultivator, the combination with a machine-frame, of arms journaled 130

thereon, drag-bars pivotally secured to the arms and consisting of two members adjustably connected together, shovels carried by the drag-bars, means for turning the arms to raise or lower the shovels, and means for turning the drag-bars upon their pivots to change the position of the shovels with respect to the longitudinal center of the machine.

3. In a wheel-cultivator, the combination with a machine - frame, of arms journaled thereon, drag-bars suspended from said arms, shovel-carrying frames carried by the drag-bars, said frames comprising arched members and rearwardly-projecting arms, said rearwardly-projecting arms being provided with slots having corrugated inner walls, shovels, a corrugated head secured to the shovels and adapted to be received by the slots, and means for turning said arms to raise or lower the shovels.

4. In a wheel-cultivator, the combination with a machine - frame, of arms journaled thereon, drag-bars comprising members adjustably connected together and adjustably suspended from the arms, shovels carried by the drag-bars, and means for turning the arms to raise or lower the shovels.

5. In a wheel-cultivator, the combination with a machine - frame, of arms journaled thereon, drag-bars pivotally suspended from said arms, shovels carried by the drag-bars, means for turning the drag-bars upon their pivots to change the position of the shovels, and means for turning the arms to raise the shovels from engagement with the ground.

6. In a wheel-cultivator, the combination with a machine - frame, of arms journaled thereon, drag-bars pivotally suspended from said arms, shovels carried by the drag-bars, a bar loosely mounted on the front ends of the drag-bars, a U-shaped lever having the rear end thereof bent downwardly over the rear end of the machine - frame and having the front ends thereof connected to the arms and said bar, and means for turning the drag-bars upon their pivots to change the position of the shovels.

7. In a wheel-cultivator, the combination with a machine - frame, of arms journaled thereon, drag-bars adjustably suspended from the arms, shovels carried by the drag-bars, and means for turning the arms to raise or lower the shovels.

8. In a wheel-cultivator, the combination with a machine - frame, of arms journaled thereon, drag-bars comprising two members adjustably connected, shovels carried by the drag-bars, shafts carried by said drag-bars and pivotally journaled in said arms to have vertical adjustments, means for connecting the drag - bars in pairs, a link connecting said means, a lever fulcrumed on the arms and having the forward end connected to said link, a bar loosely mounted on the front ends of the drag-bars, and a U-shaped lever having its forward ends connected to said bar and its rear end bent downwardly over the rear end of the machine-frame.

9. In a wheel-cultivator, the combination with a machine - frame, of arms journaled thereon, drag-bars pivotally and adjustably suspended from said arms, shovels carried by the arms, means for turning the arms to raise or lower the shovels, and means for turning the drag-bars upon their pivots to change the position of the shovels.

10. In a wheel-cultivator, the combination with a machine - frame, of arms journaled thereon, drag-bars comprising members each having one of its ends bent to engage the adjacent members, means for adjustably connecting the members, shafts carried by the drag - bars to be adjustably journaled upon the arms, shovels carried by the drag-bars, means for turning the arms to raise or lower the shovels, and means for turning the drag-bars to change the position of the shovels.

In testimony whereof I have signed my name to this specification in the presence of two subscribing witnesses.

RASMUS PEDERSON.
